DESIGN FOR A MIRROR

Ellis J. De Hart, Saginaw, Mich.

Application July 20, 1933. Serial No. 48,766

Term of patent 7 years

To whom it may concern:

Be it known that I, ELLIS J. DE HART, a citizen of the United States, residing at Saginaw, county of Saginaw, State of Michigan, have invented a new, original, and ornamental Design for Mirrors, of which the following is a specification, reference being had to the accompanying drawing, forming part thereof.

Fig. 1 is a front perspective view of a mirror showing my new design.

Fig. 2 is a sectional view, taken on the line X—X of Fig. 1.

Fig. 3 is a top plan view of the same.

The article is in the nature of a highly polished piece of metal to be used as a mirror or reflector for automobiles.

I claim:

The ornamental design for a mirror substantially as shown and described.

ELLIS J. DE HART.
